TOOL FOR CLEANING PLUMBING TRAPS AND PIPES

Aaron J. Levine, 1247 Belmont Ave., Chicago, Ill.

Filed June 6, 1958, Ser. No. 51,221

Term of patent 14 years

(Cl. D9—2)

Fig. 1 is a perspective view of a tool for cleaning plumbing traps and pipes showing my new design;

Fig. 2 is a top plan view thereof; and

Fig. 3 is a cross sectional view taken along the line 3—3 of Fig. 1, looking in the direction of the arrows and drawn to an enlarged scale.

The side of the tool opposite that shown in Fig. 1 is a mirror image of the side shown.

The dominant features of the design reside in the portions shown in full lines.

I claim:

The ornamental design for a tool for cleaning plumbing traps and pipes, as shown and described.
